UNITED STATES PATENT OFFICE.

ROBERT H. HASSSLER, OF INDIANAPOLIS, INDIANA, ASSIGNOR, BY MESNE ASSIGNMENTS, TO HASSSLER MANUFACTURING CO., INC., OF INDIANAPOLIS, INDIANA, A CORPORATION OF DELAWARE.

REBOUND CHECK.

Application filed December 18, 1925. Serial No. 76,295.

The present invention relates to improvements in rebound checks or stabilizers of the type in which a spring is utilized for increasing the resistance of relatively movable friction elements and a spring is also utilized for returning the moved element to normal position. My specific improvement is in the provision of a common spring adapter or seat for one end of each of the 10 springs. In the embodiment to be described, one of the springs is a compression spring and the other a torsion spring, and due to the adjustability of the adapter, the force of both springs may be regulated in a simple manner. Hereby the stabilizer may meet various operating conditions.

In the accompanying drawings—

Fig. 1 shows a stabilizer of the type contemplated in position at one end of a vehicle 20 chassis,

Fig. 2 is a vertical section of Fig. 1, the vehicle spring being omitted,

Fig. 3 is a view of the stabilizer with the cover removed.

Fig. 4 is a section in part of Fig. 3,

Fig. 5 shows the anchoring means for the outer end of the spiral torsion spring, and

Fig. 6 is a view of the adapter cap.

In Figs. 1 and 2, 10 indicates a side element of the chassis frame and 11 a main spring pivoted thereto. In the combination as shown, the stabilizer proper is attached to the frame and adapted to be oscillated by the actuating strap 12 fastened at one end 35 to the vehicle axle and at its other to the outer periphery of the drum 13 of the stabilizer. As may be seen from Fig. 1, the drum 13 has a projecting plate 14 while the strap 12 has two protective plates 15 and 16 at its end, these latter and the strap being slotted so as to fit over plate 14 and being held thereon by means of a split pin 17 passing through a hole in the plate 14. This arrangement is contrary to the usual practice 45 of passing the strap within the drum and is an important feature in excluding all foreign matter from the working parts.

The drum 13 is formed of two dished annuli 13' and 13'' backed up and riveted together as at 18. These rivets also secure a dished annulus 19 which has the conical faces 19' and 19'', inverted with respect to each other. A circular back plate 20 fits

into the rear of the drum section 13' and has a spacing boss 20' through which passes a 55 screw 21. The screw 21 passes through an aperture in frame element 10 and is secured by a nut 21'. A projection 22 of the back plate passes under frame element 10 in contact therewith to prevent rotation of the 60 back under strain.

On its front face the back plate has rigidly secured thereto, coaxially, an annulus 23, Fig. 2, of impregnated wood having conical faces mating with the faces 19' and 19'' of 65 annulus 19. This annulus 23, which may be termed the main friction element, has a series of blind holes 23' in its rear face into which project studs 24 fixed in the back plate 20. Rotation of element 23 is thus 70 prevented.

A further annulus, 25, of impregnated wood, which may be termed thrust member, bears against a face 26 of the annulus 19. The back plate 20 has a central boss 27 extending centrally through the described ensemble. This boss 27 has four axially extending grooves 27' (Figs. 2 and 4) into which take the lugs 28' of a thrust plate 28 whereby rotation of the latter is prevented. 75 A compression spring 29 loosely surrounds boss 27 and is compressed between thrust plate 28 and the adapter cap 30. This latter is held in place by a cap screw 31 extending through a central hole therein and 80 engaging in a threaded axial bore of the boss and by studs 30' engaging in grooves 27' for preventing its rotation, Figs. 2, 3 and 6.

From the description thus far, it will be 90 seen that, upon relative rotation of the drum 13 and back plate 20, a resistance will occur due to friction between thrust member 25 and thrust plate 28 or face 26, or both (member 25 being a floating member), and 95 between faces 19', 19'' and member 23.

The drum having been thus rotated, as on the vehicle rebound, means are necessary to return the drum to normal position, that is, to rewind the strap. For this purpose I provide a spiral torsion spring 32 having sufficient force to return the drum against the constant resistance of the friction elements. One bent end of this spring is retained in an axially extending slot 30'' of 105 the spring adapter 30, see Fig. 6; while the

other bent end is retained by a plate 33 riveted as at 33' to the vertical flange of the drum.

It will be noted from Figs. 2 and 6 that 5 the adapter cap is of cylindrical shape, the lugs 30' being riveted in the head and spaced to engage the symmetrically disposed grooves 27', Fig. 4. The cap can thus assume, in the present instance, four different 10 angular positions relative to the boss 27. The slot 30" may thus be selectively positioned to assume the correct relation to the inner end of the torsion spring. This is of importance in securing the proper 15 amount of wrap of the strap 12 on drum 13 and the proper force of spring 32. The extent to which screw 31 is tightened determines the strength of spring 29. In most cases, however, this screw will be entirely 20 seated, as shown.

The configuration of plate 33 may be most clearly seen from Figs. 3 and 5. The plate has a base flange riveted, as stated above, to the drum. The upright portion of the plate 25 is concentric with the drum, Fig. 3, and is spaced from the wall of element 13" by a little more than the thickness of the spring. The outer end of spring 32 is held between the plate and the drum wall while its extremity is engaged under projection 36 or 36', according to the direction in which its 30 force is to be exerted. This retaining means serves to hold the spring in proper position under flexure, that is, prevents any tendency 35 to travel to one side or another of the drum.

The stabilizer as described is designed to work in a constant bath of grease and upon assembling drum 13" is completely filled. The friction faces are reached by means of 40 a system of ducts, communicating with grease connection 37. This feature need not be described here as it has been set forth and claimed in a separate application. A felt washer 38 prevents the extrusion of grease 45 from the drum and the entrance of foreign matter from without.

Having thus described my invention, I claim:

1. In a rebound check, an annular conical 50 friction element, a drum comprising oppositely disposed cylindrical flanged discs, a hub supporting member, a conical friction cup mounted on said drum and engaged with the friction element, spring means for forcing the friction cup against said friction element, a member for oscillating said flanged discs, and means for securing one end of 55 said member to the flanged discs of said drum externally thereof.

2. In a rebound check, a hub supporting 60 member, a friction element mounted on said member, an oscillating drum having a friction surface thereon to frictionally engage said friction element, a horizontally disposed hub carried by said hub supporting member,

a spirally wound spring mounted on said hub, and a frictional thrust bearing interposed between said spring and the friction surface of said drum.

3. In a rebound check, an annular conical 70 friction element, an oscillating drum, a hub supporting member, a conical friction cup non-rotatably mounted on said drum and engaged with the friction element, a conical thrust bearing for transmitting pressure to 75 the friction cup, spring means for forcing the conical thrust bearing against the friction cup, and a pressure plate interposed between the spring and the thrust bearing.

4. In a rebound check, an annular conical 80 friction element, an oscillating drum, a conical friction cup, said cup secured to and arranged to oscillate with said drum, said friction cup having conical friction surfaces of varied diameters, a pressure exerting 85 spring for forcing the cup into engagement with the friction element, and a conical bearing interposed between said spring and the smaller of the surfaces on said friction cup.

5. In a rebound check, a hub supporting 90 member, an annular conical friction element mounted on said hub supporting member, an oscillating drum, a conical friction cup mounted on said drum and arranged to frictionally engage said friction element, a horizontally disposed hub carried by said hub supporting member, a spirally wound spring mounted on said hub, and a conical thrust bearing interposed between said spring and 95 said friction cup.

6. In a rebound check, a hub supporting member, an annular conical friction element nonrotatably mounted on said hub supporting member, an oscillating drum, a conical friction cup mounted on said drum and arranged to frictionally engage said friction element, a horizontally disposed hub carried by said hub supporting member, a spirally wound spring non-rotatably mounted on 100 said hub, and a conical thrust bearing interposed between said spring and said friction cup.

7. In a rebound check, an annular conical friction element, an oscillating drum, a hub supporting member, a conical friction cup mounted on said drum and engaged with the friction element, spring means for forcing the friction cup against said friction element, and means for oscillating said drum, said oscillating drum comprising a pair of oppositely disposed cylindrical flanged discs. 115

8. In a rebound check, an annular conical friction element, a drum comprising oppositely disposed cylindrical flanged discs, a hub supporting member, a conical friction cup mounted on said drum and engaged with the friction element, spring means for forcing the friction cup against said friction element, a flexible member for oscillating 120 said flanged discs, and oppositely disposed 125

angle plates interposed between said flanged discs for securing said flexible member thereto.

9. In a stabilizer, cooperating rotary friction elements, means for positively inducing a movement of one of said elements relative to the other, a torsion spring for returning the actuated element to normal position, a boss fixed to one of said elements and extending through an aperture in the other, means for rigidly securing one end of said spring with said apertured element, a member fixable on said boss in various angular positions relative thereto, and means for engaging the other end of said spring with said member.

10. In a stabilizer, cooperating rotary friction elements, means for positively inducing a movement of one of said elements relative to the other, a torsion spring for returning the actuated member to normal position, a boss fixed to one of said elements and extending through an aperture in the other, a plurality of axially-extending grooves on the periphery of said boss, a member surrounding said boss and having a lug adapted to engage said grooves selectively, means for rigidly securing one end of said spring with said apertured element, and means for engaging the other end of said spring with said lugged member.

11. In a stabilizer, cooperating rotary friction elements, means for positively inducing a movement of one of said elements relative to the other, a spiral spring for returning the actuated element, a boss fixed to one of said elements and extending through an aperture in the other, said boss having equally spaced axially-extending peripheral grooves, a member surrounding said boss and having lugs adapted to selectively engage a plurality of said grooves whereby said member is adapted to assume different angular positions relative to said boss, means for rigidly securing said spring with said apertured element, and means for engaging said spring with said lugged member.

12. In a stabilizer, cooperating rotary friction elements, means for positively inducing a movement of one of said elements relative to the other, a torsion spring for returning the actuated element to normal position, a boss fixed to one of said elements and extending through an aperture in the other, a compression spring bearing with one end on said apertured member, means for engaging one end of said torsion spring with said apertured member, and means fixable on said boss and forming a common seat for the other end of each of said springs.

13. In a stabilizer, cooperating rotary friction elements, means for positively inducing a movement of one of said elements relative to the other, a torsion spring for returning the actuated element to normal position, a

boss fixed to one of said elements and extending through an aperture in the other, a compression spring bearing with one end on said apertured member, means for engaging one end of said torsion spring with said apertured member, means fixable on said boss and forming a common seat for each of said springs, and means for altering the fixed position of said fixable means for adjusting the force of said compression spring.

14. In a stabilizer, cooperating rotary friction elements, means for positively inducing a movement of one of said elements relative to the other, a torsion spring for returning the actuated element to normal position, a boss fixed to one of said elements and extending through an aperture in the other, a compression spring bearing with one end on said apertured member, means for engaging one end of said torsion spring with said apertured member, means fixable on said boss and forming a common seat for each of said springs, and means for altering the fixed position of said fixable means for adjusting the force of said torsion spring.

15. In a stabilizer, cooperating rotary friction elements, means for positively inducing a movement of one of said elements relative to the other, a torsion spring for returning the actuated element to normal position, a boss fixed to one of said elements and extending through an aperture in the other, a compression spring bearing with one end on said apertured member, means for engaging one end of said torsion spring with said apertured member, means fixable on said boss and forming a common seat for each of said springs, and means for altering the fixed position of said fixable means for adjusting the force of both of said springs.

16. In a rebound check, a supporting plate having a hub extending therefrom, a friction element supported by and secured to said hub having a conical friction surface, an oscillating drum mounted with respect to said supporting plate so as to extend about the periphery thereof, whereby said plate and drum will provide a housing for said check, a retaining strap secured to the outer periphery of said drum adapted to be wound thereabout, a second friction element secured to said drum and having a conical friction face in frictional engagement with said first-mentioned conical face and freely rotatable with respect to said hub, and a spiral spring having one end secured to the free end of said hub and the other end to said drum for returning the elements to normal position after being actuated.

17. In a rebound check, a supporting plate having a hub extending therefrom, a friction element supported by and secured to said hub having a conical friction surface, an oscillating drum mounted with respect to said supporting plate so as to extend about

- the periphery thereof, whereby said plate and drum will provide a housing for said check, a retaining strap secured to the outer periphery of said drum adapted to be wound thereabout, a second friction element secured to said drum and having a conical friction face in frictional engagement with said first-mentioned conical face and freely rotatable with respect to said hub, a spiral spring for 10 returning the actuated elements to normal position, one end of said spring being secured to the free end of said hub, and means for gripping a substantial length of said spring at the other end thereof and securing 15 it to said drum.
18. In a rebound check, a supporting plate having a hub extending therefrom, a friction element supported by and secured to said hub having a conical friction surface, 20 an oscillating drum mounted with respect to said supporting plate so as to extend about the periphery thereof, whereby said plate and drum will provide a housing for said check, a retaining strap secured to the 25 outer periphery of said drum adapted to be wound thereabout, a second friction element secured to said drum and having a conical friction face in frictional engagement with said first-mentioned conical face and freely
- rotatable with respect to said hub, a spiral 30 spring for returning the actuated elements to normal position, one end of said spring being secured to the free end of said hub, and means for connecting the outer end of said spring to the inner periphery of said drum, 35 including a channel plate secured thereto for gripping a substantial length of said spring.
19. In a rebound check, a rigid supporting member adapted to be secured to a vehicle having an inwardly extending hub centrally positioned with respect thereto, an oscillating drum-shaped member adapted to telescope over the peripheral edge of said supporting member, means for detachably securing a flexible strap to the external peripheral 40 surface of said oscillating member, a friction disc comprising an impregnated wood block having a central conical recess formed therein, a conical metal disk adapted to seat in said recess and having its external conical surface in frictional engagement with the internal conical surface formed by said recess, and a spiral spring having its inner end secured to the free end of said hub and its outer end to the inner surface of said drum- 45 like member for returning said members to normal relative position after being actuated. 50
